MARINE DRIVE LUBRICATING SYSTEM

Edward Leipert, West Hampton Beach, N.Y.

Application April 25, 1958, Serial No. 730,946

7 Claims. (Cl. 184—6)

This invention relates to lubrication systems for use in connection with marine propulsion drive units and particularly to systems for lubricating mechanisms within separate but interconnected chambers of the drive unit.

The propeller section of marine propulsion units, being submerged at all times, remains cooler than the balance of the propulsion device. Lubricant within the submerged section therefore is cooler than that in the rest of the system. During the early stages of operation the lubricant in the propeller section is often too cold while the lubricant in the remainder of the system may, after prolonged operation get too hot for effective lubrication.

Presently known systems employ one chamber for the lubricant in the submerged section and a separate chamber for the upper gear housing. Each of the chambers in such systems requires its own type of lubricant and each lubricant has to be sealed off from contaminating the other.

Accordingly, it is an object of the present invention to provide a lubricating system for marine drives which will reduce the temperature of the lubricant within the portions of the structure which tend to overheat and at the same time raise the temperature of the lubricant in those portions of the drive where undesired cooling takes place.

Another object of the present invention is to provide a lubricating system for marine drives wherein the lubricant is continuously circulated between the excessively hot and undesirably cold structures to provide a suitable lubricant temperature at all times.

A further object of the present invention is to provide a lubricating system which will reach all of the internal portions of the drive requiring lubrication.

Another object of the present invention is to provide a simplified marine lubricating system which is carried entirely within the structure of the propulsion device.

Still another object of the present invention is to provide a lubricating system which will not interfere with the steering or other operation of the drive structure of the propulsion device.

A feature of the present invention is its use of a small pump preferably located within the propeller housing for circulating the lubricant.

Another feature of the present invention is its use of the submerged portion of the drive housing as a heat exchange unit for reducing the temperature of the lubricating substance therein.

Still another feature of the present invention is its pressure release structure for preventing undesirable build-up of pressure within the lubricating system under conditions of excessively cold lubricant.

A feature of the present invention is its longitudinally bored drive shaft for transferring the lubricant from the submerged portion of the propulsion device to the remainder of the structure.

The invention consists of the construction, combination and arrangements of parts as herein illustrated, described and claimed.

In the accompanying drawings, forming a part hereof are illustrated two forms of embodiment of the invention and in which:

Figure 1 is a view in rear elevation of a complete embodiment of the present invention partially broken away to show the construction thereof.

Figure 2 is a view in side elevation of the propeller housing shown in Figure 1 on a somewhat enlarged scale partially drawn in section to illustrate the function of the respective parts thereof.

Figure 3 is a fragmentary view similar to Figure 1 showing a second embodiment of the present invention.

Referring to the drawing and particularly to Figure 1, 10 indicates the bottom structure of a boat having the 15 housing 11 of a marine propulsion device attached thereto. The marine propulsion device consists of a gear housing 12, a drive shaft housing 13, and a propeller gear housing 14. The gear housing 12 which is located near the upper portion of the propulsion device, is formed with a 20 lubricant receiving reservoir 15 therein. The reservoir 15 maintains a desired quantity of lubricant 16 in contact with the gears 17 at all times resulting in a splash type of lubrication within the gear housing 12. The two gears 17 (only one of which is shown in Figures 1 and 25 3) receive power from the motors (not shown) through the shafts 18, and in turn transmit torque through the horizontal gear 22 to the vertical propeller shaft 19. The propeller shaft 19 is splined as indicated at 21 to the gear 22 and extends downwardly into the propeller gear 30 housing 14. The shaft 19 is centrally bored as indicated at 20 for a hereinafter described purpose.

The vertical shaft 19 terminates in a bevel gear 23 which is in mesh with a vertical bevel gear 24 (best shown in Figure 2). The bevel gear 24 is secured to the horizontal propeller shaft 25 for the purpose of driving the 35 propeller (not shown).

The propeller gear housing 14 forms a chamber 26 which serves as a reservoir for the lubricant 16 carried within this portion of the system.

40 A small pump 27 is disposed within the chamber 26 beneath the vertical shaft 19. The small pump 27 may be of the eccentric vane type (shown), gear type, or any other known form of oil pump. The outlet passage or 45 pressure side of the pump 27 is disposed adjacent the end of the longitudinal bore 20 of the vertical shaft 19. The inlet or suction side 28 of the pump 27 is located well within the lubricant 16 carried in the chamber 26. The vane 29 of the pump 27 is rotated by means of a coupling between the horizontal shaft 25 and the pump.

50 When the propulsion device is in operation the pump 27 will move the lubricant from the chamber 26 up through the bore 20 and out of the top of the vertical shaft 19, as indicated by the arrows 30 at the top of the shaft in Figure 1. The lubricant will then descend under 55 the action of gravity and pass between the various moving parts within the gear case housing 12 such as the ball bearing assembly 31 and between the teeth of the gears 17 and 22. The lubricant 16 will find its way into the reservoir 15 within the gear housing 12 to further lubricate the moving parts which rotate therethrough. A constant 60 level of lubricant 16 is maintained within the reservoir 15 by an overflow pipe 32 which is carried within the gear housing 12 and through which passes the vertical shaft 19. The excess lubricant 16 will flow into the overflow pipe 32 and downwardly in the direction of the propeller gear housing 14. A certain amount of the lubricant 16 will, as indicated by arrows, pass between the rotatable 65 drive shaft housing 13 and the lower end of the fixed gear housing 12 which supports the rotatable housing 13, thus lubricating this part of the mechanism. All of the excess lubricant will eventually find its way down through the propulsion drive structure and into the reservoir within

70

the chamber 26, lubricating the various elements it encounters during its downward travel.

Since the propeller gear housing 14 is submerged in relatively cool water at all times during the operation of the propulsion device there will be a heat exchange relationship between the oil or lubricant 16 within this housing 14 and the surrounding water. The heat exchange effected will cool the lubricant contained therein. On the other hand, the rapidly churning bevel gears 17, located within the gear housing 12, together with the other rotating parts which create friction heat will tend to overheat the lubricant 16 within the reservoir 15. The herein-described device therefor will operate to constantly transfer lubricant from the cooling chamber housing 14 to the portion of the propulsion device which tends to overheat the lubricant. After a period of running, a stabilized oil temperature will be brought about whereby all of the lubricant within the system will be at a temperature suitable for its purposes. The lubricant carried within the gear housing 12 will not be excessively hot and the lubricant within the propeller housing 14 will be heated to permit greater efficiency of operation of the gears and other moving parts within it.

It will be noted that the vertical propeller shaft 19 adjacent the discharge end of the pump 27 is provided with a beveled orifice 33. It will also be apparent that the vertical shaft 19 is secured by means of splines 21 to the horizontal bevel gear 22. A spline connection is also provided between the vertical shaft 19 and the bevel gear 23 located at the lower end of said shaft. As a result of the splined attachment of the vertical shaft between the gears 22 and 23, the shaft in effect floats freely within limits in the propulsion device. In the event that the pump 27 builds up an excessive pressure of lubricant, due to the flow resistance of cold oil through the bore 20 the orifice 33 will be unable to receive it and the entire vertical shaft 19 will be moved upwardly and away from the outlet end 34 of said pump. The lubricant 16 will then escape laterally and fall back into the chamber 26 of the gear housing 14.

Figure 3 illustrates a second embodiment of the present invention in which the lubricant is led through the gear housing 12 by means of bores or ducts 35. The lubricant is brought up through the central bore 20 of the vertical shaft 19 as has been previously described and then takes a path indicated in Figure 3 by the arrows 36. The bores 35 are provided in the structure of the housing 12 and in the upper housing cover 37 to enable the lubricant to reach all of the moving parts within the housing 12. As the oil flows down through the housing 12 and towards the bottom reservoir within the chamber 26 it is directed by the bores 35 into contact with all of the portions of the mechanism requiring lubrication.

An oil shield 38 is disposed within the bearing 39 and is provided with a small hole to permit only a small amount of the lubricant to enter the bearing 39 and to cause the major portion of the lubricant to follow the path indicated by the arrows through the bores and into contact with the remainder of the mechanism.

It will be seen from the disclosure made in connection with Figure 3, that the lubricating system employed is a directed one rather than a splash type as illustrated in connection with Figure 1.

While the present disclosure has dealt with marine drive structures, it is within the purview of the present invention to employ the lubricating system herein described and illustrated in other forms of drive wherein the lubricant passes from one chamber having a lower temperature to one or more other chambers having substantially higher temperatures by a circulation of said lubricant whereby a suitable and highly desirable lubricant temperature can be achieved at all times.

Having thus fully described the invention, what is claimed as new and desired to be secured by Letters Patent of the United States is:

1. A marine drive lubricating system comprising, an upper gear housing, drive means in said gear housing, a normally submerged propeller gear housing, driven means in the propeller gear housing and a drive shaft housing interconnecting the gear housings, a lubricant receiving chamber in the propeller gear housing, a vertically disposed shaft in the drive housing extending from the drive means to the driven means, a longitudinal bore in said shaft, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.

2. A marine drive lubricating system comprising, an upper gear housing, drive means in said gear housing, a normally submerged propeller gear housing, driven means in the propeller gear housing and a drive shaft housing interconnecting the gear housings, a lubricant receiving reservoir in the upper gear housing, a lubricant receiving chamber in the propeller gear housing, a vertically disposed shaft in the drive housing extending from the drive means to the driven means, a longitudinal bore in said shaft, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.

3. A marine drive lubricating system comprising, an upper gear housing, drive means in said gear housing, a normally submerged propeller gear housing, driven means in the propeller gear housing and a drive shaft housing interconnecting the gear housings, a lubricant receiving reservoir in the upper gear housing, a lubricant receiving chamber in the propeller gear housing, a vertically disposed shaft in the drive housing extending from the drive means to the driven means, an overflow pipe within the reservoir and disposed around the shaft to regulate the level of the lubricant in said reservoir and direct the overflow through the shaft housing to the propeller gear housing, a longitudinal bore in said shaft, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.

4. A marine drive lubricating system comprising, an upper gear housing, drive means in said gear housing, a normally submerged propeller gear housing, driven means in the propeller gear housing and a drive shaft housing interconnecting the gear housings, a lubricant receiving and cooling chamber in the propeller gear housing, a vertically disposed shaft in the drive housing extending from the drive means to the driven means, means comprising splines on said shaft operatively engaging the drive means whereby the shaft can shift longitudinally within the drive housing, a longitudinal bore in said shaft, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.

5. A marine drive lubricating system comprising, an upper gear housing, drive means in said gear housing, a normally submerged propeller gear housing, driven means in the propeller gear housing and a drive shaft housing interconnecting the gear housings, a lubricant receiving chamber in the propeller gear housing, a vertically disposed shaft in the drive housing extending from

the drive means to the driven means, a longitudinal bore in said shaft, bores within the housings to lead the lubricant from the top of the longitudinal bore through the drive means and into the propeller gear housing chamber, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.

6. A marine drive lubricating system comprising, an upper gear housing, drive means in said gear housing, a normally submerged propeller gear housing, driven means in the propeller gear housing and a drive shaft housing interconnecting the gear housings, a lubricant receiving reservoir in the upper gear housing, a lubricant receiving and cooling chamber in the propeller gear housing, a vertically disposed shaft in the drive housing extending from the drive means to the driven means, an overflow pipe within the reservoir and disposed around the shaft to regulate the level of the lubricant in said reservoir and direct the overflow through the shaft housing to the propeller gear housing, means comprising splines on said shaft operatively engaging the drive means whereby the shaft can shift longitudinally within the drive housing, a longitudinal bore in said shaft, and pump means within the propeller gear housing, an outlet passage on the pump, said pump being in abutting relationship with the bottom end of the shaft and having its outlet passage in

register with the longitudinal bore to move the lubricant from the propeller gear housing chamber through the bore and into the upper gear housing.

7. A marine drive lubricating system comprising, an upper gear housing, drive means in said gear housing, a normally submerged propeller gear housing, driven means in the propeller gear housing and a drive shaft housing interconnecting the gear housings, a lubricant receiving and cooling chamber in the propeller gear housing, a vertically disposed shaft in the drive housing extending from the drive means to the driven means, means comprising splines on said shaft operatively engaging the drive means whereby the shaft can shift longitudinally within the drive housing, a longitudinal bore in said shaft, bores within the housings to lead the lubricant from the top of the longitudinal bore through the drive means and into the propeller gear housing chamber, and pump means within the propeller gear housing, an outlet passage on the pump, said pump being in abutting relationship with the bottom end of the shaft and having its outlet passage in register with the longitudinal bore to move the lubricant from the propeller gear housing chamber through the bore and into the upper gear housing.
